UNITED STATES PATENT OFFICE.

WILLIAM JAMES MYATT, OF BIRMINGHAM, ENGLAND.

SAFETY-RAZOR.

1,139,056.

Specification of Letters Patent.

Patented May 11, 1915.

Application filed June 17, 1912. Serial No. 704,001.

To all whom it may concern:

Be it known that I, WILLIAM JAMES MYATT, a subject of His Majesty the King of England, and residing at Birmingham, 5 in England, have invented certain new and useful Improvements in or Relating to Safety-Razors, of which the following is a specification.

This invention pertains to improvements 10 in or relating to safety razors particularly of the type in which the blade is movable to lie in alinement or substantial alinement with the handle for the purpose of stropping and cleaning the same, and the guard 15 is movable so as to fold down toward or against the handle to admit of said stropping and cleaning.

The objects of my invention are three 20 fold. Firstly the construction of a safety razor with a movable blade and guard such that not only is the blade supported or held in position by the guard when in the shaving position but the guard also acts to hold it substantially in alinement with the handle 25 for the purpose of sharpening the blade.

In the hereinafter described embodiment 30 a tooth on the guard which forms a tail-piece thereof co-acts with the blade holder for holding the same in substantial alinement with the handle, such tail-piece resisting pressure exerted by the blade tending to move the guard toward the shaving position, while movement in the other direction is resisted by the frame or rigid parts of the 35 razor.

The second object is to provide means whereby the movement of the guard or blade from the shaving to the stropping position or vice versa is accompanied by a 40 simultaneous movement of the other part to the appropriate position.

The third object is the provision of special means preferably actuated by a spring for holding or assisting in holding 45 the parts in the desired position, which means may also move or assist in moving the blade from one position to another.

A safety razor embodying the present improvements in a form which works well is 50 illustrated in the accompanying drawings.

In the accompanying drawings:—Figure 1 is a side elevation of a razor constructed according to this invention. Fig. 2 is a 55 front elevation of the same partly in section. Fig. 3 is a central transverse section, illustrating the blade in its opened position

to admit of stropping and cleaning. Fig. 4 is a front elevation of the razor opened as shown by Fig. 3. Fig. 5 is a corresponding view to Fig. 4, but showing a rear view. Fig. 6 illustrates the manner of stropping the blade while connected to the razor, and, Fig. 7 is a section through the guard on line $\alpha^4-\alpha^4$ of Fig. 4.

The present improvements are particularly adapted for use in a razor in which the blade is turned to lie in the central plane of the razor (as shown by Fig. 3) to provide for the cleaning of the razor and the stropping of the blade without detaching the same from the razor frame. According to such an embodiment a blade holder 1, of any suitable construction adapted to retain the blade 2 therein while stropping, is pivotally mounted between the upper extremities of the limbs 3 of a U-shaped frame or yoke 3^a, toothed members 4 being secured in this preferred embodiment to the holder at the ends thereof adjacent to said limbs. Beneath the holder is pivoted the guard 5, 30 which is provided about the pivot axis thereof with toothed sectors 6 which gear with the corresponding toothed members 4 on the blade holder 1 whereby upon turning the guard 5 downward the blade holder 1 is 35 simultaneously moved upward. The pivot pins 7 and 8 of the said guard and holder are suitably secured to the frame 6 by being sprung into apertures in the limbs 3 of such frame within which apertures these pins 40 rotate.

The guard 5 is in the arrangement shown normally pressed into its operative position for shaving, and consequently also the blade holder 1 by virtue of the toothed gearing 4, 45 6 by means of a spring device. According to a preferable form of such a device a bifurcated projection 9 is provided on the guard 5 at a distance forward of the pivot axis thereof, and this projection is connected by a link 10 to a spring controlled plunger or slide 11 which as shown is located within the tubular handle 14 which is secured to the bottom of the frame 3^a, the parts being illustrated as so arranged that 50 when the guard is in either the operative position for shaving as shown by Figs. 1 and 2 or the inoperative position as for stropping as shown by Figs. 3, 4 and 5, such guard is normally maintained in that position by virtue of the pivot axis of the aforesaid projection 9 and the link 10 lying in 55 100 105 110 115

the case of the first mentioned position forward of the pivot axis of the guard, or in the case of the second mentioned position rearward of the said pivot axis. The handle 14 is connected to the frame 3^a in any suitable manner and conveniently through the medium of the thimble piece 22 which passes through an aperture in said frame 3^a and is screw-threaded to engage with the internally threaded upper end of the handle 14. The said thimble piece also forms a guide for the plunger 11.

The guard and blade are adjusted so that when closed together they are in operative position for shaving, and the ratio of the toothed members 4 and 6 are such that when the guard has been moved down against the frame 3^a of the razor, the blade lies in alinement or in substantial alinement with the handle 14. As in the shaving position the guard 5 projects beyond the cutting edge of the blade 2, it is convenient to move the guard and blade into the operative position for stropping, to press the guard downward by the thumb being placed on the aforesaid projecting part of the guard. The guard thus moved downward is pressed by the spring aforesaid against the U-shaped frame 3^a as shown in Fig. 3. When so placed the blade cannot rotate in the direction away from the guard, therefore, when stropping the razor by drawing the same over a horizontally or similarly supported strop, as shown in Fig. 6, a considerable amount of pressure may be applied to the blade without rotating the holder 2 in the razor frame. When stropping the reverse side of the blade by pressing upon the guard 5, when stropping in the said manner, the blade will again be prevented from turning in the razor frame as the pressure applied to the guard 5 will be such as to prevent rotation of the blade holder. The razor is preferably so designed that when the blade and guard are in the position for stropping the tip of the blade and the part of the razor projecting farthest on either side thereof lie in the plane of the bevel of the cutting edge of the blade to thereby facilitate stropping. To move the guard and blade into shaving position, pressure may be applied to the aforesaid bifurcated projection 9 which when the guard lies down against the razor frame projects rearwardly.

The guard is adapted to protect the user from injury by the corners of the blade, and for this purpose upstanding lugs 23 may be provided on the corners of the guard 5 behind which the corners of the blade are adapted to be located. While in order that the cutting edge of the blade may be at the required distance from the guard, raised portions 24 are formed thereon upon which the blade rests, such raised portions con-

veniently taking the form of pins (see Fig. 7) screwed through the guard and preferably riveted over at their lower end.

In the illustrated arrangement the pivot pin of the said bifurcated projection 9 on the guard 5 sweeps through an arc of a circle and is adapted to lie on one side of the axis of the plunger 11 when the guard is in the shaving position, and to lie an equal distance on the other side of the said axis when the guard is turned down into the inoperative position. Thus when the guard 5 is moved downward against the frame 3^a the aforesaid spring pressed plunger 11 is first moved downward and then receives an equivalent upward movement, whereby the plunger assumes the same position for both extreme positions of the guard, a corresponding movement taking place when the guard is moved back into the operative position for shaving. In this embodiment to lock the guard and blade in either the operative position for shaving or the inoperative position, as when stropping, downward movement of the plunger or slide is prevented, and according to a convenient means of effecting this as shown a rod 13 is axially slidably mounted within the handle 14 so that it may be brought to bear against the underside of the plunger or slide 11. The said rod has conveniently secured to its lower end a cap 15 which is a sliding fit over the lower end of the tubular handle 14, and to effect the axial movement of the rod an inclined slot 16 is formed in the wall of the handle 14 with which engages a pin 17 or screw secured to the cylindrical wall of said cap 15 so that by rotating the cap, which may have a mill surface, the pin 17 or screw rides up the inclined slot 16 and moves the rod 13 against the plunger or slide 11 aforesaid, whether the guard 5 and blade 2 are closed together or opened. Preferably a collar 18 is formed at an intermediate point on the said rod 13 to form the lower abutment for the spring 19 controlling the plunger or slide 11 and also to form a guide for the said rod 13, and a depression 20 may be formed in the lower side of the slot 16 at the lower end thereof into which the pin 17 is pressed by the spring 19 aforesaid, to thereby prevent accidental movement of the rod, and a depression 21 may be formed at the other end of the slot for a similar purpose.

When the guard and blade have been turned into the stropping position and the rod 13 aforesaid moved against the plunger 11, the blade is positively locked from any movement thereby still further facilitating the stropping thereof in the manner illustrated by Fig. 6 as the blade may be applied to the strop with the desired amount of pressure without liability of the blade holder turning upon its pivot, while also

preventing any accidental opening of the guard and blade when shaving.

When the rod 13 has been moved against the plunger 11 to lock the guard in either 5 the "shaving" or "out of shaving" positions the action of the spring 19 tending to maintain the blade and guard in either of said position is not interfered with, so that the spring is capable of preventing any 10 slight play which may exist between the rod 13 and plunger 11, thereby facilitating the manufacture of the razor.

Having thus described my invention what I claim and desire to secure by Letters Patent is:—

1. A safety razor including in combination, a handle, a movable guard and a movable blade carried thereby, and coöperating means connecting said guard and blade 20 whereby the movement of the guard or blade from the shaving to the stropping position or vice versa is accompanied by a simultaneous movement of the other part to the appropriate position.
2. A safety razor including in combination, a handle, a frame, a guard and blade rotatably mounted in said frame, and means connecting the guard and blade so that by rotating one of the latter the other is simultaneously rotated in the reverse direction.
3. A safety razor including in combination, a frame, a guard and blade rotatably mounted therein, a toothed member on the guard and a toothed member secured in 35 relation to the blade and in gear with the first mentioned toothed member whereby the guard and blade are simultaneously rotated toward and away from one another by movement of either.
4. A safety razor including in combination a handle, a frame, a guard and blade rotatably mounted in such frame and means connecting the guard and blade so that by rotating one of the latter, the other is simultaneously rotated in the reverse direction to a different angular extent.

5. A safety razor having a handle, a blade movable into alinement or substantial alinement with the handle for the purpose of stropping and cleaning, a guard movable to admit of said stropping and cleaning, means comprising a spring thrust or pressure control directly effective on the guard to hold the same in the shaving position, and connecting means between the blade and the guard whereby said spring control is indirectly effective upon the blade to also hold the same in the shaving position, and means independent of the spring of said pressure arrangement whereby the blade may be positively held against substantial movement in either direction when in the stropping or cleaning position.

6. A safety razor including in combination a frame, a blade and a guard rotatably

mounted therein, means connecting the guard and blade whereby they are adapted to be simultaneously and interdependently moved toward and away from one another so that when moved away from one another 70 the guard lies against the razor frame and the blade lies in alinement with the handle, a spring normally retaining the guard and blade in the closed or opened positions, and means positively locking the guard and 75 blade in such closed and opened positions independently of and without interfering with the action of the said spring.

7. A safety razor including in combination, a frame, a blade rotatably mounted in 80 such frame and having secured in relation thereto a toothed member, a guard also rotatably mounted in said frame and having a toothed member in gear with the first mentioned toothed member the disposition of the 85 various parts of the razor being such that the guard is adapted to be moved down against the frame of the razor while the blade is simultaneously moved upward in alinement with the handle.

9. A safety razor including in combination a handle, a guard and a blade holder carried thereby, means whereby the blade may be moved into alinement with the handle and the guard down toward such 95 handle and means whereby the blade holder and guard engage one another so that by positively locking one of the rotatably mounted members in the opened position the other is also positively locked in the 100 opened position.

9. A safety razor including in combination, a frame, a blade, a guard rotatably mounted in such frame to move relatively to the blade and a cylindrical spiral spring 105 located in the handle of the razor and operating upon the guard in such manner that the guard is normally retained in either the "shaving" position or "out of shaving" position against the razor structure to allow 110 the stropping of the blade.

10. A safety razor including in combination a frame, a blade holder and a guard rotatably mounted in such frame, toothed members connecting the guard and blade 115 holder so that they may be simultaneously rotated toward or away from one another and a spring located in the handle of the razor and operating upon the guard in such manner that the guard is normally retained 120 in either the "shaving" or "out of shaving" position.

11. A safety razor including in combination a tubular handle, a frame, a blade, a guard rotatably mounted within the said 125 frame, a spring pressed plunger located within the tubular handle, and a link connecting the spring pressed plunger and the guard.

12. A safety razor including in combina- 130

tion, a U-shaped frame having an aperture therein, a blade, a guard rotatably mounted within the said frame, a ferrule passed through the aperture in said frame, such 5 ferrule having a shoulder which bears on the upper surface of the frame and having an exteriorly screw threaded surface, a handle screwed into such ferrule, a spring pressed plunger slidingly mounted within 10 the ferrule, and a link connecting the spring pressed plunger and a bifurcated projection on the guard forward of the pivot axis thereof.

13. A safety razor including in combination 15 a tubular handle, a blade holder, a pivoted guard, a spring pressed plunger located within the tubular handle of the razor, a link connecting the plunger and the guard so that when the guard is moved either from 20 the "shaving" or "out of shaving" position the plunger has a downward movement imparted thereto, and an abutment adapted to move against the underside of the plunger.

14. A safety razor including in combination 25 a handle, a blade holder, a pivoted guard, a spring pressed plunger located within the handle, a link connecting the plunger and the guard so that when the guard is moved either from the "shaving" 30 or "out of shaving" position the plunger has a downward movement imparted thereto, and an abutment adapted to move against the underside of the plunger comprising a rod having a pin and slot connection with 35 the handle by which it can be moved axially.

15. A safety razor including in combination 40 a handle, a blade holder, a pivoted guard, a spring pressed plunger located within the handle of the razor, a link connecting the plunger and the guard so that when the 45 guard is moved either from the "shaving" or "out of shaving" position the plunger has a downward movement imparted thereto, a spiral spring, and an abutment adapted

to be moved against the underside of the plunger, comprising a rod having a worm connection with the handle by which it can be moved axially and a collar on said rod forming the lower abutment for the spiral spring which bears at its upper end on the 50 said spring pressed plunger.

16. A safety razor including in combination 55 a handle, a frame, a guard and a blade holder rotatably mounted in such frame, means connecting the guard and blade holder so that they are simultaneously movable toward and away from one another, a spring 60 pressed plunger located within the handle of the razor, a link connecting the plunger and the guard so that when the guard is moved either from the "shaving" or "out of shaving" position the plunger has a downward movement imparted thereto, and an abutment adapted to move against the underside 65 of the plunger.

17. A safety razor including in combination 70 a handle, a frame, a blade holder and guard rotatably mounted in such frame, means connecting the guard and blade holder so that they may be simultaneously rotated toward and from one another, a spring 75 pressed plunger located within the handle and connected to the guard so that the guard and blade are normally retained either in the "shaving" or "out of shaving" positions, and an abutment co-operating with the said plunger for locking the guard and blade holder in either of the said positions.

18. A safety razor having a blade movable 80 into "shaving" and into "stropping" positions and a movable guard, and cooperating means connecting said blade and guard whereby either part is locked if the other is prevented from movement.
